UNITED STATES PATENT OFFICE.

ARTHUR NATHAN, OF CHARLOTTENBURG, GERMANY.

STRIKE-PLATE FOR LOCKS.

No. 893,809.

Specification of Letters Patent.

Patented July 21, 1908.

Application filed June 20, 1907. Serial No. 379,927.

To all whom it may concern:

Be it known that I, ARTHUR NATHAN, engineer, citizen of Germany, subject of the King of Prussia and Emperor of Germany, residing at 87 Goethestrasse, Charlottenburg, near Berlin, in the Kingdom of Prussia and Empire of Germany, have invented new and useful Improvements in Strike-Plates for Locks, of which the following is a specification.

The present invention relates to an improved strike plate especially adapted for use with locks of the kind described in my U. S. Patent application Serial Number 249496 and in which the bolt must first come into locking position. In such locks it is noticed that the latch and bolt remain in half locking position, when the door is closed with the handle; for in such instance the bolt is caught by the latch in half locking position when the handle is released. This disadvantage is entirely remedied by the use of this improved striking plate. It consists of a special part movably attached to the striking plate which on closing the door will prevent the latch from entering the striking plate or retain the latch in open position, in which it leaves the bolt free, until the bolt has entered into the striking plate and turns or pushes aside the movable part retaining the latch.

In the accompanying drawing such an arrangement is exemplified and explained, Figures 1 and 2 showing the device fitted to the back of the striking plate in two different positions, Figs. 3 and 4 showing the main part of the invention detached in front and side elevation respectively; Figs. 5, 6, 7 and 8 show details of the design.

The principal part of the device is the lever A separately shown in Figs. 3 and 4. This lever is pivoted on the back of the striking plate B on pin d (Figs. 5 and 6). The part a of this lever A (Figs. 1 and 2) projects into a small frame b likewise fitted to the back of the striking plate B. This frame serves as a guide and stop for the lever A on the sides c (Figs. 1 and 2). The pin d has on its square part e (Figs. 5 and 6) a spring m of the known kind (Figs. 1 and 2). This spring presses against lug 1 of the lever. On its lower part the latter has a bevel s (Figs. 3 and 4).

The operation in using the device is as follows: When the door is opened, the latch and bolt of the lock are both not in locking position or project only with their bevel, the le-

ver on the striking plate being under action of the spring m in the position shown in Fig. 1. When the door is closed, the latch and bolt will advance up to the sharp edges k (Figs. 1 and 2) of the striking plate. Now the bolt should first slide forward and this is obtained by the latch being retained by its striking against part f of the lever A, while the bolt striking with its bevel against the bevel k of the lever, passes the same and thereby moves it around its pivot. As soon as the bolt has advanced far enough the lever reaches the position shown in Fig. 2 and now also the latch can advance. If this process is observed on a lock of the kind described in the U. S. Patent application Serial No. 249496, say the type for doors of rail road carriages during the locking process, it can be noticed that the lock is held open by the lug resting against tooth. The lock therefore had the disadvantage when an ordinary striking plate was used, that latch 1 and bolt 10 would advance only for a little distance when the handle connected with the operating lever was used to close the door. By the new arrangement this disadvantage is removed, by both when the door is slammed shut or closed by the handle the latch 1 is retained by part f of the lever A, when the door closes into the frame, so that the bolt must advance first and tooth of the bolt will pass above the lug of the latch, whereby bolt and latch may come in full locking position.

Now the dimensions have been so chosen, that at any stroke of the handle and if the door is closed into the frame, the locking device must always come into locking position, as in the moment where the tooth of the bolt is going to lie before lug of the latch, the latter is retained by the lever and the tooth passes the lug. If on the other hand in opening the lock the stroke is too short, so that the lever A could not yet come into action, latch and bolt cannot remain idle as the lug is gliding on the tooth but both again enter full locking position. Instead of a lever pivotally connected with the striking plate a slide may be used rectilinearly displaceable on the striking plate.

Having now described my invention what I claim and desire to secure by Letters Patent of the United States is:

1. In a lock provided with an automatically closing bolt, the combination of means removably arranged on the striking plate for retaining the latch in unlatched position, one

portion of said means lying in the direction of the latch opening of the striking plate, the other portion of said means lying behind the bolt opening, said first mentioned portion being pushed out of the range of the latch by the advancing bolt engaging said second mentioned portion.

2. In a lock provided with an automatically closing bolt, the combination of a slide 10 attached to the striking plate, one end of said slide lying behind the latch opening of the striking plate for retaining the latch in unlatched position, and the other end of the slide lying behind the bolt opening.

15 3. In a lock with an automatically closing bolt the combination of a lever pivoted to the rear of the striking plate, means for guiding said lever, stops for limiting the stroke of

said lever, a spring in connection with said lever, said spring returning said lever into 20 its normal position when the bolt and latch are withdrawn, substantially as described.

4. A striking plate for a lock provided with an automatically closing bolt, having 25 movable means mounted thereon for retaining the latch in unlatched position, said movable means being arranged to be pushed out of the range of the latch by the advancing bolt.

In testimony whereof I have hereunto set 30 my hand in presence of two subscribing witnesses.

ARTHUR NATHAN.
